OSCAR C. KREIS, OF DETROIT, MICHIGAN, ASSIGNOR TO CONTINENTAL MOTORS CORPORATION, OF DETROIT, MICHIGAN, A CORPORATION OF VIRGINIA

SLEEVE-VALVE-ENGINE-COOLING MEANS

Application filed June 20, 1927. Serial No. 199,923.

This invention relates to internal combustion engines and refers more particularly to the sleeve valve type of engine. In this type of engine the upper extremity of the sleeve ordinarily works in a pocket formed between the cylinder head and cylinder. While the cylinder head is ordinarily jacketed for cooling water, the amount of available jacketing is limited principally because of the spark plug location and general arrangement of parts and as a result the sleeve pocket becomes overheated resulting in formation of steam pockets, carbon accumulation and general inefficient operation of the engine.

My invention overcomes the above objectionable characteristics of the sleeve valve engine by causing a positive circulation of cooling water through the cylinder head. One of the objects of my invention is to provide for such circulation in a simple and efficient manner.

Referring to the drawings in which like reference characters represent corresponding parts,

Fig. 1 is a section side elevation view longitudinally through adjacent front cylinders of the engine,

Fig. 2 is a section view through 2-2 of Fig. 1, and

Fig. 3 is a bottom plan view of a cylinder head.

In the drawings reference character A represents the engine which is illustrated as having a plurality of cylinders 10 each having the usual piston 11 and sleeve valve 12. The engine illustrated is the single sleeve valve type in which the sleeve is moved in a combined reciprocating and oscillating path to cause the sleeve intake and exhaust ports 13 and 14 to function with the cylinder intake and exhaust ports 15 and 16 respectively in a well known manner. The particular arrangement of ports and the manner of driving the sleeve valves form no part of this invention and may be of the usual well known or other preferred construction and arrangement.

The cylinders 10 are shown provided with a cooling water jacket 17 which surrounds or partially surrounds the cylinders 10, the

water being circulated through the jacket by the pump 18 which may be of any preferred construction suitably located and driven for this purpose. In Fig. 1 the pump is shown in one of its customary positions mounted on the drive shaft 19 carrying the usual fan 20 and pulley 21 which may be driven from the engine crankshaft (not shown) in the well known manner. The cooling water is supplied by pipe 22 connecting the usual radiator (not shown) and delivered to the water jacket 17 at 23.

Each cylinder is closed at the top preferably by a cylinder head B which may be formed with walls 24 and 25. The wall 24 together with the associated cylinder forms a valve pocket 26 accommodating the movement of the upper portion of the sleeve valve 12. The wall 25 is spaced from the wall 24 to form the cylinder head cooling water jacket 27 and also defines the combustion chamber 28.

In order to cause positive circulation of the cooling water throughout the cylinder head jacket 27, the cylinder head B is formed preferably at one side with an inlet 29 which communicates with one or more openings 30 leading to the water jacket 17. Such opening 30 constitutes the only means of communication between the cylinder head jacket 27 and cylinder jacket 17 whereby the water is forced to follow a definite path in its circulation as indicated by the arrows in Figs. 1 and 2. In order to further guide the water in a circulatory path down into the cylinder head jacket, across the same, and thence upwardly for discharge into the header 31, I have provided the baffles 32. These baffles prevent the water from passing directly across the cylinder head by causing the water to move downwardly below their extremities and through the openings 33 at the bottom of the cylinder head jacket whence the water passes upwardly on the other side of the baffles to the header 31 which communicates with the like discharge areas of the various cylinders and thence preferably communicates with the inlet portion of the usual radiator.

The cylinder heads B may be secured to the

respective cylinders 10 by the corner studs 34. The cover 35 preferably covers the cylinders B and forms the header 31. This cover 35 may be seated on the cylinders, being clamped in place by nuts 36 threadedly engaging the upper ends 37 of the cylinder heads. 38 represents the usual spark plug openings. If desired for appearance a top cover 39 may be provided as shown.

10 It will be apparent that I have provided simple and effective means for circulating the cooling water through the cylinder heads whereby the cylinder heads and valve pockets will be adequately cooled.

15 What I claim as my invention is:

1. A sleeve valve internal combustion engine comprising a plurality of cylinders, pistons operable within said cylinders, a water jacketing structure surrounding the cylinders, a pump for causing circulation of cooling water longitudinally of and around the cylinders in said jacket, cylinder heads fitted on said cylinders respectively each having an opening communicating with the cylinder water jacket along one side of the cylinders, the said openings constituting the only means for passage of cooling water from the cylinder water jacket to the cylinder heads, each of said cylinder heads being provided with spaced walls forming a pocket for a sleeve valve and also forming an annular cylinder head water jacket communicating with the said cylinder opening, baffles for the cylinder head jackets extending substantially longitudinally of the engine said baffles having their lower ends spaced from the bottom of the cylinder head jackets respectively whereby the cooling water from the respective openings is caused to travel downwardly beneath the baffles on one side thereof, and upwardly on the other side thereof, and a return water header communicating with the cylinder head jackets at the side of the baffles last mentioned.

45 2. A sleeve valve internal combustion engine comprising a plurality of cylinders, pistons operable within said cylinders, a water jacketing structure surrounding the cylinders, a pump for causing circulation of cooling water longitudinally of and around the cylinders in said jacket, cylinder heads fitted on said cylinders respectively each having an opening communicating with the cylinder water jacket along one side of the cylinders, the said openings constituting the only means for passage of cooling water from the cylinder water jacket to the cylinder heads, each of said cylinder heads being provided with spaced walls forming a pocket for a sleeve valve and also forming an annular cylinder head water jacket communicating with the said cylinder opening, baffles for the cylinder head jackets extending substantially longitudinally of the engine said baffles having their lower ends spaced from the bottom

of the cylinder head jackets respectively whereby the cooling water from the respective openings is caused to travel downwardly beneath the baffles on one side thereof and upwardly on the other side thereof, and a return water header communicating with the cylinder head jackets at the side of the baffles last mentioned, said return water header being otherwise substantially free from communication with the cylinder water jacket.

70 3. A sleeve valve internal combustion engine comprising in combination, a water jacketed cylinder structure provided with a water outlet at the top of the cylinder structure, a cylinder head structure seated on the cylinder structure and having an annular water jacket portion depending within the cylinder and spaced therefrom to provide a sleeve pocket, said cylinder head jacket being open upwardly at one side of the engine, said cylinder head structure having a conduit portion overlying the cylinder head jacket at the other side of the engine, said conduit being constructed and arranged to receive water from the cylinder jacket outlet for distribution 80 into said cylinder head jacket, and a cover overlying the cylinder head jacket and providing a water outlet header at the first said side of the engine.

75 4. A sleeve valve internal combustion engine comprising in combination, a water jacketed cylinder structure provided with a water outlet at the top of the cylinder structure, a cylinder head structure seated on the cylinder structure and having an annular water jacket portion depending within the cylinder and spaced therefrom to provide a sleeve pocket, said cylinder head jacket being open upwardly at one side of the engine, said cylinder head structure having a conduit portion overlying the cylinder head jacket at the other side of the engine, said conduit being constructed and arranged to receive water from the cylinder jacket outlet for distribution 90 into said cylinder head jacket, and a cover overlying the cylinder head jacket and providing a water outlet header at the first said side of the engine.

95 5. A sleeve valve internal combustion engine comprising in combination, a water jacketed cylinder structure provided with a water outlet at the top of the cylinder structure, a cylinder head structure seated on the cylinder structure and having an annular water jacket portion depending within the cylinder and spaced therefrom to provide a sleeve pocket, said cylinder head jacket being open upwardly at one side of the engine, said cylinder head structure having a conduit portion overlying the cylinder head jacket at the other side of the engine, said conduit being constructed and arranged to receive water from the cylinder jacket outlet for distribution 100 into said cylinder head jacket, and a cover overlying the cylinder head jacket and providing a water outlet header at the first said side of the engine, said cover seating on said cylinder structure adjacent said cylinder head structure.

105 6. A sleeve valve internal combustion engine comprising in combination, a water jacketed cylinder structure provided with a water outlet from the cylinder jacket at the top of the cylinder structure, a cylinder head having a water jacket portion depending within the cylinder and spaced therefrom, sleeve valve means within the said space, said cylinder head seating on top of the cylinder structure, a cylinder head jacket cover seating on the top of the cylinder structure and providing a water outlet header in communication with the cylinder head jacket at one side of the engine, and a water guiding wall beneath said cover at the other side of the engine ter.

minating above the cylinder structure adjacent the cylinder jacket outlet and cooperating with the cylinder head jacket to form a water conduit.

6. A sleeve valve internal combustion engine comprising, a jacketed cylinder, a jacketed cylinder head depending within the cylinder and having a portion seating on the cylinder, a cover over the cylinder head having a portion seating on the cylinder and forming a water outlet header at one side of the engine, said cylinder having a jacket outlet intermediate the cylinder head and cover seating portions, and a wall beneath the cover at the other side of the engine terminating adjacent the cylinder jacket outlet also intermediate the cylinder head and cover seating portions, said wall guiding water from the cylinder jacket outlet toward the cylinder head jacket.

In witness whereof, I hereunto subscribe my name this 17th day of June, A. D. 1927.

OSCAR C. KREIS.
